The ornamental design for an armature lamp fixture, as shown and described.

DESCRIPTION

FIG. 1 is a perspective view of an armature lamp fixture showing my new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof;

FIG. 7 is a bottom plan view thereof;

FIG. 8 is an additional right side elevational view thereof, with the armature lamp fixture shown disposed differently as a sconce; and,

FIG. 9 is an additional right side elevational view thereof, with the armature lamp fixture shown disposed differently as a hanging pendant.

The broken line disclosure in the views represents environmental structure which forms no part of the claimed design.
